[57] ABSTRACT

Novel dithiobiurets of one of the following formulas:

and

where R, R₁, R₂, and R₃ are certain organic radicals, the ring

contains 5–8 atoms, and A, E, and G are alkylene, and salts of these dithiobiurets.

An exemplary compound: 1,1-dimethyl-2-thio-3-[(4-propylpiperazin-1-yl)-thiocarbonyl]urea.

6 Claims, No Drawings

1,1-DIMETHYL-2-THIO-3-(4-ALKYL-PIPERAZINO)-THOCARBONYL UREAS

BACKGROUND OF THE INVENTION

Japanese Pat. application No. 43-54280/1968, published Mar. 25, 1971, as Pat. application Publication No. 46-11679/1971 discloses a class of dithiobiurets of the general formula

where R^1 and R^2 can be hydrogen or lower alkyl and R^4 can be hydrogen, lower alkyl, cyanoalkyl, formyl, acetyl, halogen acetyl, and pyridyl. These compounds are said to be useful as insecticides, housefly 20 antifertility agents, and mite-killing agents.

It has been found, however, that these compounds exhibit undesirable levels of phytotoxicity. It is this problem that the compounds of the present invention have overcome. Compounds of the present invention 25 provide excellent protection against mites without causing any significant damage to the treated plants.

SUMMARY OF THE INVENTION

This invention is a class of novel miticidal compounds which can be represented by the following formulas:

Ia

and

Ib

where:

A is

a is 0 through 4;

b is 1 or 2;

E is

d is 2 through 5;

e is 1 or 2; with the provision that the total number of atoms in the ring

is between 5 and 8, inclusive;

R is alkyl of 1 through 6 carbon atoms; with the provision that the sum of carbon atoms in A , E , and R is not more than 10;

G is

m is 0 through 6;

n is 1 or 2;

R_1 is methyl, $-(CH_2)_2-NR_2R_3$ or $-(CH_2)_3-NR_2R_3$;

R_2 is methyl or ethyl;

R_3 is alkyl of 1 through 6 carbon atoms;

R_2 and R_3 taken together can be $-(CH_2)_p-$; and p is 4 through 6; with the provision that the sum of carbon atoms in G , R_1 , R_2 , and R_3 is not more than 10; and

salts of the above compounds with acids or bases, the acids being selected from those having an ionization constant of at least 1×10^{-7} and the salts formed with bases containing a cation selected from Li^+ , Na^+ , K^+ , CA^{++} , Cu^{++} , Zn^{++} , Mg^{++} , Mn^{++} , and

40

where

R_4 , R_5 , and R_6 can be the same or different and each can be hydrogen, alkyl of 1 through 4 carbon atoms, or hydroxy alkyl of 2 through 4 carbon atoms; and R_7 is hydrogen, alkyl of 1 through 12 carbon atoms, benzyl, amino, methylamino, or dimethylamino; R_4 and R_5 can be taken together to form a ring that is $-(CH_2)_2-O-(CH_2)_2-$ or $-(CH_2)_j-$ where j is 4-6 and R_6 and R_7 are H.

50 Examples of such acids include HCl , HBr , HF , HI , H_2SO_4 , $HSCN$, H_3PO_4 , H_2SO_3 , acetic acid, oxalic acid, tartaric acid, benzoic acid, and N-lauryl-N-methyl-2-aminoethane sulfonic acid.

55 In addition to the miticidal utility of the compounds of the present invention, they may be used to prepare the class of compounds which comprise the subject matter of copending U.S. patent application Ser. No. 358,395 filed simultaneously herewith by Russell F. Bellina, which compounds are disclosed therein as being useful for the protection of plants from mites, fungi, aphids, Colorado potato beetle, Mexican bean beetle, and boll weevil.

For the sake of clarity it is mentioned that while the compounds of the present invention are, in fact, dithiobiurets and are identified generically as such, the various species within the scope of the present invention are identified as thiocarbonyl ureas and thiocarbamoyl ureas in order to permit the orderly and systematic naming of said species.

DETAILED DESCRIPTION OF THE INVENTION

Preferred Compounds

Certain of the compounds of Formulas Ia and Ib are preferred because of their ease of synthesis and higher activity. These compounds include those compounds of Formula Ia where:

A and E are $-(CH_2)_2-$; and
R is alkyl of 1 through 4 carbon atoms;

and salts thereof;

and those compounds of Formula Ib where:

G is $-(CH_2)_2-$ or $-(CH_2)_3-$;

R₁ is methyl;

R₂ is methyl or ethyl;

R₃ is methyl or ethyl;

and salts thereof.

Compounds within this scope that are most preferred include:

1,1-dimethyl-2-thio-3-[(4-methylpiperazin-1-yl)-thiocarbonyl]urea

sodium salt of 1,1-dimethyl-2-thio-3-[(4-methylpiperazin-1-yl)-thiocarbonyl]urea

hydrobromic acid salt of 1,1-dimethyl-2-thio-3-[(4-methylpiperazin-1-yl)-thiocarbonyl]urea

1,1-dimethyl-2-thio-3-[(4-propylpiperazin-1-yl)-thiocarbonyl]urea

1,1-dimethyl-2-thio-3-[N-(2-dimethylaminoethyl)-N-methyl-thiocarbamoyl]urea

1,1-dimethyl-2-thio-3-[N-(3-dimethylaminopropyl)-N-methyl-thiocarbamoyl]urea

triethanolamine salt of 1,1-dimethyl-2-thio-3-[(4-methylpiperazin-1-yl)-thiocarbonyl]urea

Synthesis of the Compounds

The compounds of Formulas Ia and Ib can be prepared by the general procedure described in U.S. Pat. No. 3,166,564 and further described in *J. Med. Chem.* 14, 772 (1971) i.e.; by reacting an appropriate substituted thiocarbamoyl chloride with an alkali metal or ammonium thiocyanate to form the corresponding substituted thiocarbamoyl isothiocyanate and then reacting the latter with an appropriate secondary amine.

The salts of these compounds can be prepared by mixing an equimolar amount of the desired acid or an equimolar amount of the desired base with the appropriate dithiobiuret in a suitable solvent.

The following examples are given to illustrate the above-described processes. All parts are by weight unless specified otherwise.

EXAMPLE 1

Preparation of

1,1-dimethyl-2-thio-3-[(4-propylpiperazin-1-yl)-thiocarbonyl]urea

A solution of 12 parts of N-propylpiperazine in 50 parts of acetone was added dropwise to a solution of 14.2 parts of dimethylthiocarbamoyl isothiocyanate in 100 parts of acetone at 10° to 15°C. The solution was

then allowed to warm to room temperature, stirred for approximately 2 hours, and then filtered.

The solvent was removed under vacuum and the residue dissolved in 50 parts of 10% sodium hydroxide. 5 The aqueous solution was washed twice with 50 parts of chloroform and then acidified with glacial acetic acid to about pH 7. The acidified solution was then extracted twice with 50-part portions of methylene chloride. The hydrocarbon layers were combined, dried over anhydrous magnesium sulfate, filtered, and the solvent was then removed under reduced pressure to give 13.5 parts of 1,1-dimethyl-2-thio-3-[(4-propylpiperazin-1-yl)-thiocarbonyl]-urea as a viscous oil.

15

EXAMPLE 2

Preparation of

1,1-dimethyl-2-thio-3-[N-(2-dimethylaminoethyl)-N-methyl-thiocarbamoyl]urea

20

A solution of 10.2 parts of N,N,N'-trimethyl ethylene diamine in 20 parts of acetone was added dropwise to 14.2 parts of dimethylthiocarbamoyl isothiocyanate in 100 parts of acetone at 10°-15°C. The solution was allowed to warm to room temperature, stirred for an additional 2 hours, and then filtered.

25

The solvent was removed under reduced pressure and the residue was dissolved in a mixture of 100 parts of chloroform and 50 parts of 10% aqueous sodium hydroxide solution. This mixture was shaken and then separated. The aqueous layer was acidified to about pH 7 with glacial acetic acid and then extracted three times with 50 part portions of methylene chloride. These extracts were combined, dried over anhydrous magnesium sulfate, filtered, and the solvent was removed therefrom under reduced pressure to give 13 parts of the crude product. Crystallization from ethanol gave 5 parts of pure 1,1-dimethyl-2-thio-3-[N-(2-dimethylaminoethyl)-N-methyl-thiocarbamoyl]urea, m.p. 93°-94°C.

30

EXAMPLE 3

Preparation of

1,1-dimethyl-2-thio-3-[N-(3-dimethylaminopropyl)-N-methyl-thiocarbamoyl]urea

35

A solution of 11.6 parts of N,N,N'-trimethyltrimesylenediamine in 30 parts of acetone was added dropwise to 14.2 parts of dimethylthiocarbamoyl isothiocyanate in 100 parts of acetone at 10°-15°C. The solution was allowed to warm to room temperature and then stirred for an additional hour.

40

The solvent was removed under reduced pressure and the residue was recrystallized twice from ethanol to give 3.2 parts of crystalline 1,1-dimethyl-2-thio-3-[N-(3-dimethylaminopropyl)-N-methyl-thiocarbamoyl]urea, m.p. 108°-110°C.

EXAMPLE 4

Preparation of

1,1-dimethyl-2-thio-3-[(4-methylpiperazin-1-yl)-thiocarbonyl]urea

45

A solution of 100 parts of N-methylpiperazine in 100 parts of acetone was added dropwise to 142 parts of dimethylthiocarbamoyl isothiocyanate in 650 parts of acetone at 10°-15°C. The resulting solution was allowed to warm to room temperature and stirred for 16 hours, during which time a solid precipitated. The solid

material was filtered off to give 120 parts of 1,1-dimethyl-2-thio-3-[(4-methylpiperazin-1-yl)-thiocarbonyl]urea, m.p. 160°C. dec.

By using the appropriate amine, the following dithiobiurets can be prepared similarly:

- 1,1-dimethyl-2-thio-3-[(4-methyl-1,4-diazacyclohept-1-yl)-thiocarbonyl]urea
 1,1-dimethyl-2-thio-3-[(4-pentyl-1,4-diazacyclohept-1-yl)-thiocarbonyl]urea
 1,1-dimethyl-2-thio-3-[(2-methyl-1,2-diazacyclohept-1-yl)-thiocarbonyl]urea
 1,1-dimethyl-2-thio-3-[(2-propyl-1,2-diazacyclopent-1-yl)-thiocarbonyl]urea
 1,1-dimethyl-2-thio-3-[(2-hexyl-1,2-diazacyclohex-1-yl)-thiocarbonyl]urea
 1,1-dimethyl-2-thio-3-[(2,3-dimethyl-1,2-diazacyclopent-1-yl)-thiocarbonyl]urea
 1,1-dimethyl-2-thio-3-[(2-hexyl-3-methyl-1,2-diazacyclopent-1-yl)-thiocarbonyl]urea
 1,1-dimethyl-2-thio-3-[(2,5-dimethyl-1,2-diazacyclopent-1-yl)-thiocarbonyl]urea
 1,1-dimethyl-2-thio-3-[(3,4,5-trimethylpiperazin-1-yl)-thiocarbonyl]urea
 1,1-dimethyl-2-thio-3-[(2,4,6-trimethylpiperazin-1-yl)-thiocarbonyl]urea
 1,1-dimethyl-2-thio-3-[(2,4,5-trimethylpiperazin-1-yl)-thiocarbonyl]urea
 1,1-dimethyl-2-thio-3-[(2,6-dimethyl-4-isopropylpiperazine-1-yl)-thiocarbonyl]urea
 1,1-dimethyl-2-thio-3-[(3-methyl-1,3-diazacyclopent-1-yl)-thiocarbonyl]urea
 1,1-dimethyl-2-thio-3-[(3-pentyl-1,3-diazacyclopent-1-yl)-thiocarbonyl]urea
 1,1-dimethyl-2-thio-3-[(4-isopropylpiperazin-1-yl)-thiocarbonyl]urea
 1,1-dimethyl-2-thio-3-[(4-sec-butylpiperazin-1-yl)-thiocarbonyl]urea
 1,1-dimethyl-2-thio-3-[(4-ethylpiperazin-1-yl)-thiocarbonyl]urea
 1,1-dimethyl-2-thio-3-[(1,2,2-trimethylhydrazino)-thiocarbonyl]urea
 1,1-dimethyl-2-thio-3-[(1-methyl-2-ethyl-2-hexylhydrazino)-thiocarbonyl]urea
 1,1-dimethyl-2-thio-3-[N-(azacyclohept-1-yl)-N-methyl-thiocarbamoyl]urea
 1,1-dimethyl-2-thio-3-[N-(pyrrolidin-1-yl)-N-methyl-thiocarbamoyl]urea
 1,1-dimethyl-2-thio-3-[1-(2-dimethylaminoethyl)-2,2-diethylhydrazino-thiocarbonyl]urea
 1,1-dimethyl-2-thio-3-[1-(3-diethylaminopropyl)-2,2-dimethylhydrazino-thiocarbonyl]urea
 1,1-dimethyl-2-thio-3-[N-(pyrrolidin-1-yl)-N-(2-dimethylaminoethyl)-thiocarbamoyl]urea
 1,1-dimethyl-2-thio-3-[N-(pyrrolidin-1-yl)-N-[2-(pyrrolidin-1-yl)ethyl]thiocarbamoyl]urea
 1,1-dimethyl-2-thio-3-[N,N-bis(2-dimethylaminoethyl)thiocarbamoyl]urea
 1,1-dimethyl-2-thio-3-[N-(6-dimethylaminohexyl)-N-methyl-thiocarbamoyl]urea
 1,1-dimethyl-2-thio-3-[1-(2-diethylaminoethyl)-N-methyl-thiocarbamoyl]urea
 1,1-dimethyl-2-thio-3-[N,N-bis(2-dimethylaminoethyl)-thiocarbamoyl]urea
 1,1-dimethyl-2-thio-3-[N-[2-(pyrrolidin-1-yl)ethyl]N-methyl-thiocarbamoyl]urea
 1,1-dimethyl-2-thio-3-[N-[5-(pyrrolidin-1-yl)pentyl]-N-methyl-thiocarbamoyl]urea

- 1,1-dimethyl-2-thio-3-[N-[3-(N-ethyl-N-butylamino)-propyl-1]-N-methyl-thiocarbamoyl]urea
 1,1-dimethyl-2-thio-3-[(5-methyl-1,5-diazacyclooct-1-yl)-thiocarbonyl]urea
 1,1-dimethyl-2-thio-3-[(4-ethyl-1,4-diazacyclooct-1-yl)-thiocarbonyl]urea
 1,1-dimethyl-2-thio-3-[(4,5,6-trimethyl-1,5-diazacyclooct-1-yl)-thiocarbonyl]urea
 1,1-dimethyl-2-thio-3-[(2,8-dimethyl-5-ethyl-1,5-diazacyclooct-1-yl)-thiocarbonyl]urea
 1,1-dimethyl-2-thio-3-[(4,5,8-trimethyl-1,5-diazacyclooct-1-yl)-thiocarbonyl]urea
 1,1-dimethyl-2-thio-3-[N-(2-dimethylamino-1-methylethyl)-N-methyl-thiocarbamoyl]urea
 1,1-dimethyl-2-thio-3-[N-(2-dimethylamino-2-methylethyl)-N-methyl-thiocarbamoyl]urea
 1,1-dimethyl-2-thio-3-[N-(3-dimethylamino-1-methylpropyl)-N-methyl-thiocarbamoyl]urea
 1,1-dimethyl-2-thio-3-[N-(3-dimethylamino-3-methylpropyl)-N-methyl-thiocarbamoyl]urea
 1,1-dimethyl-2-thio-3-[N-[2-(pyrrolidin-1-yl)-1-methylethyl]-N-methyl-thiocarbamoyl]urea
 1,1-dimethyl-2-thio-3-[N-[3-(azacyclohept-1-yl)-1-methylpropyl]-N-methyl-thiocarbamoyl]urea

EXAMPLE 5

Preparation of the nitric acid salt of 1,1-dimethyl-2-thio-3-[(4-methylpiperazin-1-yl)-thiocarbonyl]urea

1.5 Parts of concentrated nitric acid was added to a slurry of 5.0 parts of 1,1-dimethyl-2-thio-3-[(4-methylpiperazin-1-yl)-thiocarbonyl]urea (prepared as in the process described in Example 4 above) in 10 parts of water. The resulting mixture was stirred until all the compound was dissolved and the water was then evaporated under reduced pressure. The residue was crystallized from methanol to give 0.7 parts of the nitric acid salt of 1,1-dimethyl-2-thio-3-[(4-methylpiperazin-1-yl)-thiocarbonyl]urea, m.p. 150°C. dec.

By using the appropriate acid together with the appropriate dithiobiuret, the following acid salts can be prepared similarly:

- hydrobromic acid salt of 1,1-dimethyl-2-thio-3-[(5-methyl-1,5-diazacyclooct-1-yl)-thiocarbonyl]urea
 hydrobromic acid salt of 1,1-dimethyl-2-thio-3-[(4-ethyl-1,4-diazacyclooct-1-yl)-thiocarbonyl]urea
 hydrochloric acid salt of 1,1-dimethyl-2-thio-3-[(4,5,6-trimethyl-1,5-diazacyclooct-1-yl)-thiocarbonyl]urea
 hydrochloric acid salt of 1,1-dimethyl-2-thio-3-[(2,8-dimethyl-5-ethyl-1,5-diazacyclooct-1-yl)-thiocarbonyl]urea
 hydroiodic acid salt of 1,1-dimethyl-2-thio-3-[(4,5,8-trimethyl-1,5-diazacyclooct-1-yl)-thiocarbonyl]urea
 hydroiodic acid salt of 1,1-dimethyl-2-thio-3-[N-(2-dimethylamino-1-methylethyl)-N-methyl-thiocarbamoyl]urea
 sulfuric acid salt of 1,1-dimethyl-2-thio-3-[N-(2-dimethylamino-2-methylethyl)-N-methyl-thiocarbamoyl]urea
 sulfuric acid salt of 1,1-dimethyl-2-thio-3-[N-(3-dimethylamino-1-methylpropyl)-N-methyl-thiocarbamoyl]urea

acetic acid salt of 1,1-dimethyl-2-thio-3-[N-(3-dimethylamino-3-methylpropyl)-N-methylthiocarbamoyl]urea

acetic acid salt of 1,1-dimethyl-2-thio-3-[N-(2-pyrrolidin-1-yl)-1-methylethyl]-N-methylthiocarbamoyl]urea 5

nitric acid salt of 1,1-dimethyl-2-thio-3-[N-(3-azacyclohept-1-yl)-1-methylpropyl]-N-methylthiocarbamoyl]urea

EXAMPLE 6

Preparation of the sodium salt of 1,1-dimethyl-2-thio-3-[(4-propylpiperazin-1-yl)-thiocarbonyl]urea

0.8 Part of sodium hydroxide is added to a solution of 5.5 parts of 1,1-dimethyl-2-thio-3-[(4-propylpiperazin-1-yl)-thiocarbonyl]urea in 50 parts of water. The resulting mixture can be stirred until all the solid is dissolved to give an aqueous solution of the desired sodium salt of 1,1-dimethyl-2-thio-3-[(4-propylpiperazin-1-yl)-thiocarbonyl]urea. 15

By using an appropriate base with an appropriate dithiobiuret, the following salts can be prepared similarly:

sodium salt of 1,1-dimethyl-2-thio-3-[(1,2,2-trimethylhydrazino)-thiocarbonyl]urea 25

sodium salt of 1,1-dimethyl-2-thio-3-[(1,2,2-trimethylhydrazino)-thiocarbonyl]urea

potassium salt of 1,1-dimethyl-2-thio-3-[(1-methyl-2-ethyl-3-hexylhydrazino)-thiocarbamoyl]urea 30

potassium salt of 1,1-dimethyl-2-thio-3-[N-(azacyclohept-1-yl)-N-methyl-thiocarbamoyl]urea

calcium salt of 1,1-dimethyl-2-thio-3-[N-(pyrrolidin-1-yl)-N-methyl-thiocarbamoyl]urea

calcium salt of 1,1-dimethyl-2-thio-3-[1-(2-dimethylaminoethyl)-2,2-diethylhydrazino-thiocarbonyl]urea 35

zinc salt of 1,1-dimethyl-2-thio-3-[1-(3-diethylaminopropyl)-2,2-dimethylhydrazino-thiocarbonyl]urea 40

zinc salt of 1,1-dimethyl-2-thio-3-[N-(pyrrolidin-1-yl)-N-(2-dimethylaminoethyl)-thiocarbamoyl]urea

magnesium salt of 1,1-dimethyl-2-thio-3-[N-(pyrrolidin-1-yl)-N-[2-(pyrrolidin-1-yl)-ethyl]-thiocarbamoyl]urea 45

magnesium salt of 1,1-dimethyl-2-thio-3-[N,N-bis(2-dimethylaminoethyl)-thiocarbamoyl]urea

manganese salt of 1,1-dimethyl-2-thio-3-[N-(6-dimethylaminoethyl)-N-methyl-thiocarbamoyl]urea 50

manganese salt of 1,1-dimethyl-2-thio-3-[1-(2-diethylaminoethyl)-N-methyl-carbamoyl]urea

copper salt of 1,1-dimethyl-2-thio-3-[N,N-bis(2-diethylamino)-thiocarbamoyl]urea 55

copper salt of 1,1-dimethyl-2-thio-3-[N-(2-(pyrrolidin-1-yl)ethyl)-N-methyl-carbamoyl]urea

tetramethyl ammonium salt of 1,1-dimethyl-2-thio-3-[(3,4,5-trimethylpiperazin-1-yl)-thiocarbonyl]urea

trimethyl-n-butyl ammonium salt of 1,1-dimethyl-2-thio-3-[2,4,6-trimethylpiperazin-1-yl)-thiocarbonyl]urea 60

tetra-n-butyl ammonium salt of 1,1-dimethyl-2-thio-3-[(2,4,5-trimethylpiperazin-1-yl)-thiocarbonyl]urea

trimethyl-n-dodecyl ammonium salt of 1,1-dimethyl-2-thio-3-[(2,6-dimethyl-4-isopropylpiperazin-1-yl)-thiocarbonyl]urea 65

tetraethyl ammonium salt of 1,1-dimethyl-2-thio-3-[(3-methyl-1,3-diazacyclopent-1-yl)-thiocarbonyl]urea

trimethyl benzyl ammonium salt of 1,1-dimethyl-2-thio-3-[(3-pentyl-1,3-diazacyclopent-1-yl)-thiocarbonyl]urea

tri-n-butyl benzyl ammonium salt of 1,1-dimethyl-2-thio-3-[(4-isopropylpiperazin-1-yl)-thiocarbonyl]urea

lithium salt of 1,1-dimethyl-2-thio-3-[(4-ethylpiperazin-1-yl)-thiocarbonyl]urea

EXAMPLE 7

Preparation of the triethanolamine salt of 1,1-dimethyl-2-thio-3-[(4-methylpiperazin-1-yl)-thiocarbonyl]urea

Three parts of triethanolamine is added dropwise to a slurry of 5 parts of 1,1-dimethyl-2-thio-3-[(4-methylpiperazin-1-yl)-thiocarbonyl]urea in 40 parts of water at room temperature. The resulting slightly cloudy yellow solution is then filtered to remove impurities thereby affording 48 parts of a 17% aqueous solution of the triethanolamine salt of 1,1-dimethyl-2-thio-3-[(4-methylpiperazin-1-yl)-thiocarbonyl]urea.

Similarly, by use of the appropriate amine and dithiobiuret the following salts can be prepared:

ammonia salt of 1,1-dimethyl-2-thio-3-[(4-methylpiperazin-1-yl)-thiocarbonyl]urea

methylamine salt of 1,1-dimethyl-2-thio-3-[(4-ethylpiperazin-1-yl)-thiocarbonyl]urea

dibutylamine salt of 1,1-dimethyl-2-thio-3-[(4-propylpiperazin-1-yl)-thiocarbonyl]urea

dibutanolamine salt of 1,1-dimethyl-2-thio-3-[N-(2-dimethylaminoethyl)-N-methyl-thiocarbamoyl]urea

hydrazine salt of 1,1-dimethyl-2-thio-3-[N-(2-dimethylaminoethyl)-N-methyl-thiocarbamoyl]urea

N,N-dimethylhydrazine salt of 1,1-dimethyl-2-thio-3-[N-(2-dimethylaminopropyl)-N-methyl-thiocarbamoyl]urea

methylhydrazine salt of 1,1-dimethyl-2-thio-3-[N-(2-dimethylaminopropyl)-N-methyl-thiocarbamoyl]urea

morpholine salt of 1,1-dimethyl-2-thio-3-[(4-methylpiperazin-1-yl)-thiocarbonyl]urea

piperadine salt of 1,1-dimethyl-2-thio-3-[(4-methylpiperazin-1-yl)-thiocarbonyl]urea

hexamethyleneimine salt of 1,1-dimethyl-2-thio-3-[(4-methylpiperazin-1-yl)-thiocarbonyl]urea

dodecylamine salt of 1,1-dimethyl-2-thio-3-[N-(2-dimethylaminoethyl)-N-methyl-thiocarbamoyl]urea

pyrrolidine salt of 1,1-dimethyl-2-thio-3-[N-(2-dimethylaminoethyl)-N-methyl-thiocarbamoyl]urea

benzylamine salt of 1,1-dimethyl-2-thio-3-[N-(2-dimethylaminopropyl)-N-methyl-thiocarbamoyl]urea

trimethylamine salt of 1,1-dimethyl-2-thio-3-[N-(2-dimethylaminopropyl)-N-methyl-thiocarbamoyl]urea

The use of the compounds of the present invention as miticides is the subject matter of copending U.S. patent application Ser. No. 358,396 filed simultaneously herewith by Colin L. McIntosh. A complete description of formulations and methods of application of these

compounds is contained therein and is hereby incorporated herein by reference.

Use of the Compounds as Intermediates

The compounds of the present invention can be used as intermediates in the preparation of the corresponding dithiazolium salts. This reaction can be carried out under the general conditions described in U.S. Pat. No. 3,166,564 for oxidation of dithiobiurets in the presence of an acid to produce dithiazolium salts. These salts and their use as miticides, fungicides, and plant protectants are the subject matter of the above-mentioned copending U.S. patent application Ser. No. 358,395 which is a continuation-in-part of U.S. patent application Ser. No. 304,793, filed Nov. 8, 1972.

What is claimed is:

1. A compound of the formula.

Wherein R is alkyl of 1 to 6 carbon atoms or salts of these compounds with acids or bases, the acids being selected from those having an ionization constant of at least 1×10^{-7} and the salts formed with bases containing the cation selected from Li^+ , Na^+ , K^+ , $\text{Ca}^{++}\text{Cu}^{++}$,

5

Zn^{++} , Mg^{++} , Mn^{++} , and

where R_4 , R_5 , and R_6 , are the same or different and represent hydrogen, Alkyl of 1 through 4 carbon atoms or hydroxyl alkyl of 2 through 4 carbon atoms; R_7 is hydrogen, alkyl of 1 through 12 carbon atoms, benzyl, amino, methylamino, or dimethyl amino; R_4 and R_5 taken together to form a ring that is $-(\text{CH}_2)_2-$ or $-(\text{CH}_2)_j-$ where j is 4-6 and R_6 and R_7 are H.

15 2. Compound of claim 1 which is hydrobromic acid salt of 1,1-dimethyl-2-thio-3-[(4-methylpiperazin-1-yl)-thiocarbonyl]urea.

3. Compound of claim 1 which is 1,1-dimethyl-2-thio-3-[(4-propylpiperazin-1-yl)-thiocarbonyl]urea.

20 4. Compound of claim 1 which is 1,1-dimethyl-2-thio-3-[(4-methylpiperazin-1-yl)-thiocarbonyl]urea

5. Compound of claim 1 which is the sodium salt of 1,1-dimethyl-2-thio-3-[(4-methylpiperazin-1-yl)-thiocarbonyl]urea.

25 6. Compound of claim 1 which is the triethanolamine salt of 1,1-dimethyl-2-thio-3-[(4-methylpiperazin-1-yl)-thiocarbonyl]urea.
